UNITED STATES PATENT OFFICE

2,109,128

CLOSURE OPERATOR

Jesus Leal Carrillo, Long Beach, Calif.

Application October 15, 1935, Serial No. 45,138

1 Claim. (Cl. 121—44)

This invention relates to operating devices, for doors, windows, or analogous devices and among the objects of the invention is to provide a simple and efficient means for shifting the closure to either open or closing position.

In accordance with the present invention, the closure operator consists broadly in the provision of a cylinder having a piston mounted for reciprocation therein and connected with the closure for opening and closing the same, together with novel valve means for controlling the supply and exhaust of air to the cylinder for reciprocating the piston.

The invention, together with the objects and advantages, will be best understood from the following description taken in connection with the accompanying drawings, wherein—

Figure 1 is an elevational view illustrating the application of the invention to a door.

Figure 2 is an end elevational view of the cylinder.

Figure 3 is a sectional view thru the cylinder showing the manner of connecting the piston with the door.

Figure 4 is a detailed sectional view on the line 4—4 of Figure 3.

Figure 5 is an end elevational view of the piston.

Figure 6 is a longitudinal, sectional view through the cylinder and piston illustrating certain details hereinafter more fully referred to.

Figure 7 is a detailed, sectional view through the cylinder showing the means for sealing the slot provided in the cylinder as and for the purpose hereinafter more fully disclosed.

Figure 8 is a detailed, sectional view through a valve control for the operator.

Figure 9 is a fragmentary side elevation view of the valve control.

In the illustrated embodiment thereof the invention is shown as applied to a sliding door. Thus referring to the drawings in detail, it will be seen that 5 indicates generally a sliding door.

In accordance with the present invention there is suitably mounted in the adjacent wall and the upper casing of the door opening an elongated cylinder 7. Fitted on the end of the cylinder are caps 8 provided with apertured flanges 9 through the medium of which, and through other fastening devices 10, the caps are secured with the cylinder 9 in position.

Mounted for reciprocation within the cylinder 7 is a piston, consisting as shown, of a body 11 having pins 12 projecting from relatively opposite ends thereof as shown. Through the medi-

um of the pins 12 and nuts 13 there are secured on relatively opposite ends of the body of the piston, packing rings 14 and cup washers 15.

Suitably mounted within the respective opposite ends of the cylinder 7 and carried by the caps 8 are rubber covered bumpers 16 which limit the movement of the piston 11.

The piston body 11 has formed integrally therewith a stepped lug 17 having a sliding fit in stepped grooves 18 provided in the bottom of the cylinder at opposite sides of the longitudinally extending slot 19.

Integral with the lug 17 is a shank 20 terminating in a depending substantially U-shaped shoe or attaching member 21. The shoe or attaching member 21 straddles an upper forward corner of the door 5 as best shown in Figures 3 and 4, and through the medium of rivets or other fastening devices 22 said shoe is positively secured to the door 5 for transmitting movement of the piston to the door.

Connected to and within the respective opposite ends of the cylinder 7 as at 23, is an elongated spring metal tape 24 that is of a width to substantially close the slot 19 as shown in Figure 7. The tape 24 is trained through a suitable opening 25 provided therefor in the aforementioned lug 17 as clearly shown in Figures 4 and 5. The peripheries of both the packing members 14 and the cup washers 15, at their lower diametrical points, bear upon the tape 24 and hold the latter in sealing position upon both sides of the shank 20 and piston body 11. It will be seen that pressure on the tape 24 will tend to seal the slot 19 behind the piston 11 against which air pressure is exerted for moving the piston in one direction.

Extending upwardly through one side of the door casing, and leading from any suitable source of air supply is a pipe 26 which has an end 26a connected with an inlet 27 on one of the caps 8. Branching from the pipe 26 is a pipe 26b that is connected with an inlet 28 provided on the other of the caps 8. The caps 8 are provided with exhausts 29 and 30 respectively.

Provided in the pipe end 26a, and pipe branch 26b, are manually operable valves 31.

Each of the valves 31, as clearly shown in Figure 8, consists of a suitable cylindrical casing 32 in which is mounted for reciprocation a suitable valve 33, (Figure 8), normally urged in one direction through the medium of a spring 34. On one end the valve 33, (Figure 8), is provided with a suitable push button or stem 35. It is thought that the operation of the device will

be clear from the foregoing. However the operation may be briefly set forth as follows:

- With the door in the closed position as shown in Figure 1, opening of the door is effected as follows. The operator presses in on the button 5 of the valve 31 associated with the pipe end 26 so that air from the source of supply will flow from the pipe 26 through the pipe end 26a into the cylinder 7 at the left-hand end of the cylinder and thereby act on the piston 11 to move the latter towards the right. Obviously, as the piston moves in this direction, door 5 will move therewith in a corresponding direction to open position.
- With the door in an open position, it may be moved to a closed position by the operator pressing the push-button 35 of the valve 31 arranged in the pipe branch 26. The air under pressure will then flow from the pipe 26 through the branch 26b into the cylinder 7 at the right hand of the cylinder and thereby act on the piston 11 to move the same toward the left. Obviously as the piston 11 moves in the direction for moving the door to a closed position, air at the left hand side of the piston will exhaust from the cylinder 7 through the exhaust 29, thus permitting the

piston to move freely in the direction indicated for closing the door 5. In this connection it will be noted that in the opening of the door 5 air in the cylinder 7 will exhaust through the exhaust 30.

Having thus described the invention, what is claimed is:

In a device of the class described, a cylinder provided with an elongated slot therein, the sides of said slot being stepped inwardly, a piston mounted for reciprocation in said cylinder, said piston having a shank extending therefrom and operating in said slot, the sides of the shank being stepped to register with the stepped sides of the slot, means for connecting the respective ends of the cylinder with a source of air supply for reciprocating said piston, and means for sealing the slot in the cylinder without impairing the reciprocatory movement of the cylinder, said means including a flexible tape anchored at its respective opposite ends to said cylinder, said tape extending longitudinally in said slot and said shank having an opening therethrough accommodating said tape.
